UNITED STATES PATENT OFFICE

ARTHUR C. PRESTON, OF WILBRAHAM, AND GEORGE C. GRESS, OF SPRINGFIELD, MASSACHUSETTS, ASSIGNORS TO THE FIBERLOID CORPORATION, OF INDIAN ORCHARD, MAINE, A CORPORATION OF MASSACHUSETTS

METHOD OF DIGESTING NITROCELLULOSE

Original application filed July 13, 1928, Serial No. 292,555. Divided and this application filed May 6, 1929. Serial No. 360,854.

This invention relates to improvements in the method of digesting or cooking nitrocellulose. This application is a division of an application Serial No. 292,555, filed by us July 13, 1928.

Nitrocellulose material to be most suitable for use in manufacturing must of course be thoroughly digested or cooked. To accomplish this according to one method it is confined in a closed vat and a heated cooking liquid is circulated therethrough, as for instance, by a pump which discharges the liquid into the lower side of the vat and has its suction connected to the upper side thereof. By this method the liquid circulates up through the material and uniformly permeates the same and at the same time tends to prevent the material settling in the vat, provides uniform distribution of heat throughout the mass and carries dangerous gases of decomposition away. It has been found that in order to produce the best digesting results, it is most desirable to maintain the temperature of the liquid at a considerable temperature somewhat above the boiling temperature, say 270 degrees Fah. and at a pressure of approximately 30 pounds per square inch.

Due to various causes there usually develops a loss of pressure so that the pressure at the suction side of the pump is less than that at the discharge side thereof so that under the temperature and pressure conditions as stated there is a tendency for the liquid to flash into steam. The result of this flashing is that the desired circulating of the liquid is interrupted, the material is not uniformly cooked, explosions are likely to occur in connection with the gases which are formed by the decomposition of the material, and being no longer carried upward positively to a vent, may become localized at points in the mass undergoing digestion.

Therefore the principal object of this invention is the provision of a method for digesting nitro-cellulose and the like wherein the cooking liquid may be maintained in circulation at the desired pressure and at a temperature above the boiling point of water. To this end the benefits of a high cook-

ing temperature may be taken advantage of and at the same time the dangers usually present when explosive gases are developed as with the old method referred to may be eliminated.

The novel features of our invention are accomplished by means of a novel mode of operation and apparatus to be hereinafter more fully described in the form at present preferred and which for illustrative purposes may be taken in connection with the accompanying drawing in which:

The figure represents a digesting apparatus and circulating pump therefor with the novel features of our invention associated therewith.

In order to facilitate a clear understanding of the method of the invention the apparatus shown in the drawing will now be described in detail.

A supply pipe 5 leading into one branch of a Y fitting 6 is provided which has a valve 7. This pipe is arranged for conducting nitro-cellulose to an opening at the lower end of the digester D while a shut-off valve 9 between the Y fitting 6 and digester is provided. The nitro-cellulose or other material to be digested may be delivered to the pipe line 5 from any convenient location and allowed to flow by gravity or pumped under pressure to the digester as may be desired. It will be understood that the material is preferably conducted through the pipe by a liquid which may be called a carrying liquid, which liquid may be water or whatever is desired or necessary to carry the liquid or to serve as a cooking or digesting liquid.

A screen 10 preferably in the form of a perforated plate, metal cloth or the like, is fixed to a frame 11, which is suspended by chains 12 from hooks not shown at the upper end of the digester. This screen may be supported by the chains so that its edges will abut the inner walls of the digester and when in place it serves to prevent the material being digested from passing out through the outlet 13 at the upper side of the digester.

A pipe connection 14, in communication with the outlet 13, is connected to a T fitting F, while valves 15 and 16 at the outlet of the

T fitting F are arranged so that liquid from the digester may be directed either downwardly through a circulating pipe 18 or outwardly through a waste pipe 19, as will later appear.

A pipe 20 in communication with the upper end of the digester is connected to a pressure relief valve 21, which valve may be of any well-known form adapted to open at some predetermined pressure and allow the escape of pressure from the digester.

A pipe 22 extending from the cover 3 is provided with a shut-off valve 24 and is connected to the lower side of a closed expansion tank 25. This tank is adapted to accommodate the ordinary fluctuations of pressure within the system during the digesting operation and is connected by a pipe 26 to the relief valve pipe 20 so that any excessive pressure will be released through said relief valve. A pipe such as shown, or other means, may be provided on control by a valve to permit a predetermined amount of pressure and/or gases to escape from tank 25.

A filling pipe 27 controlled by a valve 28 and leading into the upper side of the expansion tank is arranged for delivering water or other liquid to the said tank 25.

A steam line 33, which may be connected to any suitable source of supply, is arranged to conduct the same to the circulating pipe 18. The admission of steam to the pipe 18 is preferably controlled by a shut-off valve 34 and a thermostatically controlled valve 35, while a check valve 36 prevents or checks a flow of pressure from the pipe 18 to the pipe 33 and steam system connected thereto. A downwardly directed pipe or tube 37 is provided within the pipe 18 for directing the steam from the line 33 downwardly in the pipe 18 in the direction of flow of fluid circulating through the system.

The valve 35 may be of the electrically operated type in common use and may be actuated or controlled by thermostatic elements 38 of ordinary form located in the T fitting F. The particular form of the valve 35 and actuating means therefor is not important for the practice of the invention, it being intended to indicate that in the operation of the apparatus it is desirable and necessary to have the control of the admission of steam under control of the temperature prevailing in the digester and system.

The pipe 18, at its lower end, is connected to a valve 40 adjacent the Y fitting 6 and to the inlet or suction side 41 of a pump P. The pump P may be of any desired form, centrifugal or otherwise, and may be operatively connected to any power supplying means such as a motor M shown.

A pipe 45 in communication with the outlet side of the pump P is connected by means of the connection 46 to a pipe 47 which is connected to the Y fitting 6 and to a discharge

riser 48. Valves 49 and 50 of the pipes 47 and 48 are provided so that the material delivered or discharged by the pump may be directed either to the digester 2 or the discharge line 48.

Nozzles or jets 55 extending through the lower end of the digester are connected to a pipe 56 surrounding the digester and a supply pipe 57 leading thereto which may be connected to any suitable water or fluid supplying system. A valve 58 of the pipe 57 will control the flow of fluid to the jets for the purpose to be described.

In the operation of the apparatus thus described the valves 15, 7, 28, 40 and 50 are closed so that the carrying liquid is circulated up through the vat and nitrocellulose by the pump and back again to the pump.

In the operation of the apparatus, at relatively low pressures and temperatures, a slight relative difference in pressure between the suction and discharge sides of the pump is not likely to produce the undesirable effects referred to. When operating however at relatively high temperatures or above the boiling point as is desirable for best results the flashing ordinarily occurs. To obviate this condition we provide means for adding pressure to the system so as to compensate for any drop in pressure referred to which brings about the undesirable results. This may be accomplished in one way by means of an air pump 60 which is connected to a storage tank 62 that is in turn connected by suitable piping 64 to the expansion chamber 25 as shown. A regulating valve of any well-known form represented at 66 may be inserted in the connection 64 for regulating or controlling the pressure delivered to the expansion chamber 25 by the pressure system.

Having described the operation of the apparatus it will be observed that the digesting liquid may be maintained at the desired working temperature while by superposing a pressure on the system the tendency for the liquid to flash into steam is obviated.

The specific form of apparatus may be changed or modified within wide limits without departing from the scope of the invention and we prefer therefore to be limited, if at all, by the appended claims rather than by the foregoing description.

What we claim is

1. The method of digesting nitro-cellulose which consists in, confining the nitrocellulose in a closed system, circulating a digesting liquid therethrough, heating said liquid and in admitting air pressure to said system to bring the pressure therein above that at which the said liquid will flash into steam.

2. The method of digesting nitrocellulose which consists in, confining said nitrocellulose in a closed system, subjecting the material to the action of a digesting liquid, heating said liquid, venting the system to allow the escape

of explosive gases and in imposing pressure on the digesting liquid in said system to compensate for the escape of gases and prevent the flashing of the liquid into steam.

5 3. The method of digesting nitro-cellulose which consists in, confining said material in a closed system, circulating digesting liquid through said system and heating said liquid above its boiling point and in imposing air in
10 said liquid from a source outside said system at a pressure which will bring the pressure in said system above that at which said liquid will flash into steam.

15 4. The method of digesting nitro-cellulose which consists in, confining nitro-cellulose in a part of a closed system, circulating a digesting liquid through the said nitro-cellulose and the said system, heating said liquid and in admitting air pressure to said system to bring
20 the pressure therein above that at which the said liquid will flash into steam.

In testimony whereof we affix our signatures.

ARTHUR C. PRESTON.
GEORGE C. GRESS.
